STARTING DEVICE, PARTICULARLY FOR
INTERNAL COMBUSTION ENGINES

Wilhelm Pabst, Hamburg, Germany

Application June 10, 1938, Serial No. 213,104
In Germany June 25, 1937

3 Claims. (Cl. 121—37)

The invention refers to starters for internal combustion engines, and in particular to starters that can be fed by some means of pressure, such as air or gas, from a pressure chamber or an explosive cartridge.

The required starting moment is effected by a piston moving axially, which displaces either two sleeves each provided with inside spiral rifling or one sleeve with inside and another with outside spiral rifling, whereby the inner rifling with smallest average diameter works in co-operation with a suitably rifled shaft attached to the bottom of the cylinder, the second rifling of the piston being engaged with a suitably rifled driving shaft or sleeve that bears at its front end the coupling teeth for the starting claw.

In the accompanying drawings, like characters of reference indicate like parts in the several views, and:

Figure 1 is a vertical section taken diametrically through the axis of the device;

Figure 2 is a fragmentary section on the line 2—2 of Fig. 1;

Figure 3 is an elevation showing a portion of the piston stem;

Figure 4 is an axial section through Fig. 3;

Figure 5 is a side elevation of a carrier or intermediate sleeve used herein; and

Figure 6 is an axial section through Fig. 5.

The action in this case is as follows:

The piston 1, which is firmly connected with the sleeve 20 provided with inside and outside rifling 26 and 27, respectively, slides on the one hand on the inner guide surface of the cylinder 4 and on the other hand on the cylindrical part of the axially arranged shaft 6 which is rigidly connected to the head of the cylinder. The free end of the shaft 6 is reduced and has keyed thereon for longitudinal sliding movement a cylindrical carriage 29. A plug 30 closes the free end of shaft 6 and provides a flange 30a to limit the sliding movement of the carriage 29 in one direction. Movement of the carriage 29 in the other direction is limited by the shoulder 29a at the inner end of the reduced portion of shaft 6. The outer surface of carriage 29 is provided with rifling 28 which is in constant mesh with the inner rifling 26 of the sleeve 20. A driving sleeve 21 is slidably and rotatably mounted in the lower end of the casing 4, the amount of sliding being limited by stops 31, 32, 33 to correspond to the amount of sliding permitted carriage 29. A torsion spring 34 has one end connected to the member 30 carried by the stationary shaft 6 and has its other end connected as at 35 to the lower

and closed end of the driving sleeve 21. This spring is torsioned during downward movement of the piston and acts to assist in restoring the member 21 to its normal position upon upward movement of said piston. The carriage 29 is keyed to the shaft 6 as at 36. To further explain the operation of the device, the shaft 6 is rigidly mounted within the outer casing 4 and is not rotatable. In casing 4, guided through part 6, the piston 1 can then slide with its sleeve 20 both in longitudinal direction as well as by means of a rotating movement. At first the sleeve 20 can only move in a longitudinal direction at the time when forces affect the head of the piston 1, said forces pressing downwardly because the carriage 29 slides longitudinally along the guide shaft 6 and is not rotatable thereon. The pressure on the piston 1 can at first move sleeve 20 and carriage 29 downwardly until the latter reaches collar 30a of the plug 30 of guide shaft 6 and contacts it. This stops automatically the longitudinal movement, and piston 1 can only further yield to the pressure and continue a downward movement when the thread 26 of the piston 1 rotates on the thread 28 of the guide carriage 29. Only at this moment does a rotating movement of the piston 1 occur.

The effect of the device will then be as follows:

The action on the piston 1 may be caused by the pressure gases entering at 7. When the piston has then been brought in the above stated manner to the rotating point, by which also sleeve 20 rotates, which has the outer rifling 27, the rotating movement is transmitted to the driving sleeve 21 whose rifling 25 engages rifling 27. This gives driving sleeve 21 any desired number of rotations for each stroke of piston 1 in accordance with the pitch selected for the rifling.

When piston 1 has passed ports 12, the pressure gases escape into the open air and spring 14 of the valve 15 opens the valve which also permits the escape of gases. The return of piston 1 to the rest position shown in the drawings is then caused by pressure spring 16 and the operation is complete. The pressure gases entering at 7 drive the piston forward, whereby the piston slides away from the cylinder head, carrying with it the carriage 29 and driving sleeve 21 until the carriage engages stop 30a. The keyed connection between carriage 29 and shaft 6 prevents rotation of the sleeves 20 and 21 during this movement. When the carriage 29 engages stop 30a, the sleeve 20 of piston 1 is given

a twist by the riflings 28 on carriage 29 engaging into the corresponding interior rifling 26 of the sleeve, this twist being in turn transmitted to the driving sleeve 21. As the driving sleeve 21 is provided with riflings 25 which engage into the corresponding outer riflings 27 of the sleeve 20, the driving sleeve 21 is given an extra twist in addition to that of piston 1, so that by this arrangement the driving sleeve 21, which bears at the other end the coupling teeth 9, can make any desired number of revolutions during the whole stroke of piston 1. The number of revolutions depends solely on the choice of the pitch of the individual riflings.

After having traversed its full stroke during the starting process, piston 1 uncovers the exhaust ports 12 of shaft 6, so that the pressure gas can escape into the open air through the ports 12 and the bore 13. Owing to the drop of the pressure caused by the opening of ports 12, the spring 14 of the valve 15 comes into predominance and opens the valve 15, so that the consumed gases may also escape through the opening 14a of the valve spring housing 14b and then through the port 14c in the head 4a of the cylinder 4. Owing to this complete release of the pressure gases the spring 16 is able to take the whole piston 1 with the sleeve 20 back to its above position of rest.

Before the piston 1 reaches its upper position of rest the valve 15 is closed again by the piston striking the stop 19. In a renewed starting process the highly compressed gases then keep the valve 15 closed until a decrease of the gas pressure again takes place through the escape of the gases through the opening 12.

What I claim is:

1. In a starting device of the kind described, a cylindrical casing having a fixed end, a centrally disposed hollow cylindrical guide shaft fixed at one end to the center of the fixed end and projecting toward the opposite end of the cylinder, steeply pitched spiral threads on the free end portion of the exterior of the guide shaft, a piston fitting in said cylinder and having an elongated hub forming a sleeve, said sleeve having internal grooves engaging said threads, a driven shaft actuated by the movement of said sleeve, said guide shaft having a smoothly cylindrical portion extending from the fixed head to said threaded portion to effect smooth guidance of the piston and to prevent escape of gas between the piston and sleeve, and

means to limit movement of the piston by pressure of fluid admitted between the fixed head and piston and comprising ports in said guide shaft opening into the hollow interior thereof, said ports being uncovered by said piston adjacent the end of the stroke thereof.

2. In a starting device of the kind described, a cylindrical casing having a fixed end, a centrally disposed hollow cylindrical guide shaft fixed at one end to the center of the fixed end and projecting toward the opposite end of the cylinder, a guide carriage slidably keyed on the free end of said shaft, means limiting the sliding of said carriage on said shaft, steeply pitched spiral threads on the periphery of said carriage, a piston fitting in said cylinder and having an elongated hub forming a sleeve, said sleeve having internal grooves engaging said threads, a driven shaft actuated by the movement of said sleeve, said guide shaft having a smoothly cylindrical portion extending from the fixed head to said keyed end portion to effect smooth guidance of the piston and to prevent escape of gas between the piston and sleeve, means to limit movement of the piston by pressure of fluid admitted between the fixed head and piston and comprising ports in said guide shaft opening into the hollow interior thereof, said hollow interior opening directly to the atmosphere, said ports being uncovered by said piston adjacent the end of the stroke thereof, an escape valve in said fixed head, spring means effecting opening of said escape valve upon passage of the piston to position to open said ports, and means to effect closing of said valve upon movement of the piston to normal position.

3. In a starting device of the kind described, a cylindrical casing, an axially disposed cylindrical guide shaft fixed at one end to one end of said casing and projecting toward the opposite end of said casing, a driving sleeve rotatably fitted in said opposite casing end, a guide carriage slidably keyed on the free end of said shaft, steeply pitched spiral threads on the periphery of said carriage, a hollow piston fitting in said cylindrical casing, an axial sleeve on said piston surrounding said shaft, the inner surface of said sleeve having internal grooves engaging said threads of said carriage, and the periphery of said sleeve having spiral threads, said driving sleeve having internal grooves in constant mesh with said peripheral threads of said first sleeve.

WILHELM PABST.
